UNITED STATES PATENT OFFICE.

FRANK GUELCHER, OF BROOKLYN, NEW YORK.

IGNITION SYSTEM.

Application filed March 14, 1925. Serial No. 15,614.

To all whom it may concern:

Be it known that I, FRANK GUELCHER, a citizen of the United States, residing at Brooklyn, in the county of Kings, State of New York, have invented certain new and useful Improvements in Ignition Systems; and I do hereby declare the following to be a full, clear, and exact description of the invention, such as will enable others skilled 10 in the art to which it appertains to make and use the same.

My invention relates to an improved ignition system for internal combustion engines and, more particularly, to ignition 15 systems for automobiles.

The principal object of my invention is to provide an ignition system of such a character that when a distributor, contact breaker or other part of the apparatus be- 20 comes out of order, it is not necessary to repair the disarranged or broken parts before operating the engine again. My invention contemplates the provision of at least two complete ignition systems and 25 means whereby these two systems can be connected to the spark plugs of the engines selectively by simply operating a simple lever or its equivalent.

My invention includes two separate and 30 distinct distributors, each connected to all of the spark plugs of the engine. This connection may be permanent, or it may be effected through a suitable switch which may or may not be operated when the connections 35 are changed to alter the manner in which electrical energy is supplied to the spark plugs. A contact breaker may be associated with each distributor and a driving means is provided for actuating the distributors 40 and contact breakers. Manually operated means is provided for connecting the driving means to either of the distributors at will.

I prefer to employ a battery for supply- 45 ing current to the distributors, and to supplement this current supply with two magneto's or generators driven in properly timed relation with respect to the distributors. The battery or either one of the generators, or the combination of one of the generators and the battery can be used for 50 supplying current to the distributor which is intended to supply current to the engine

at any given time. A switch is provided in the circuit which connects the battery to the distributors and to the generators, and this switch is arranged so as to be actuated by the lever or rod which controls the driving mechanism for the distributors.

My invention can be best understood by 60 considering the following detailed description which is to be taken in conjunction with the accompanying drawings in which—

Figure 1 is a circuit diagram of my im- 65 proved ignition system.

Figure 2 is a transverse section view of the driving mechanism.

Figure 3 is an elevation of one of the clutch members and

Figure 4 is an elevation of the companion 70 clutch member.

In the accompanying drawings, which are largely diagrammatic, I have illustrated at 1 an internal combustion engine, such as the ordinary automobile engine. The crank 75 shaft of this engine is shown at 2. A plurality of spark plugs, *a*, *b*, *c* and *d* are arranged in the well-known manner for the purpose of supplying the ignition current to the engine.

A distributor 3, spark coil 4 and contact breaker 5 are provided for the purpose of supplying current to the spark plugs *a*, *b*, *c* and *d*. A battery 6 is connected so as to supply current to the primary winding of the coil 4, the circuit being as follows: battery 6, lead 7, ammeter 8, switch 9, lead 10, switch 11, lead 12, contact breaker 5, lead 13, primary winding of coil 4 and back to the battery 6 through grounded connections. The secondary winding of the coil 4 is arranged to be connected to leads 14, 15, 16 and 17 by the rotating arm 18 of the distributor 3, and the leads 14, 15, 16 and 17 are, in turn, connected to the spark plugs *a*, *b*, *c* and *d* through the switch 11. The switch 11 is of the double throw variety and is provided with ten poles or contacts. Four of these poles, *a'*, *b'*, *c'* and *d'* are connected to the leads 14, 15, 16 and 17 and corresponding fingers of the movable element of the switch are connected to the spark plugs *a*, *b*, *c*, and *d*, as shown in Figure 1.

The pole *e'* is connected to the contact 105 breaker 5 by means of the lead 12 and the

corresponding finger of the movable element of switch 11 is connected to the battery lead 10.

A manually operable rod 19, which can be arranged so as to be operated conveniently by the driver of the vehicle, serves as a means for operating the switch 11.

A generator 20 which can be driven by the crank shaft 2 of the engine is arranged to supply current to the contact breaker 5 and the spark coil 4. The generator or magneto 20 supplies current to the contact breaker 5 through the lead 21. The circuit connecting the magneto 20 with the spark coil is completed through grounded connections in the usual manner.

The magneto 20, distributor 3 and contact breaker 5 are all driven by the engine crank shaft through connecting apparatus which includes a shaft 22. A clutch member 23 is splined to this shaft. The companion clutch member 24 has a gear or sprocket wheel 25 attached thereto. The drive shaft 2 supplies power to the sprocket wheel 25 through a counter-shaft 26 and chains 27 and 28. A lever 29 connects the clutch member 23 with the manually operable controlling rod 19. The arrangement is such that when the rod 19 is moved in the direction indicated by the arrow in Figure 1, the clutch members 23 and 24 are brought into engagement and the shaft 22 is caused to rotate.

The clutch members 23 and 24 are preferably constructed in some such manner as indicated in Figures 3 and 4, the object being to make these members so that they will not engage except when they occupy a certain position. This insures the proper timing of the magneto 20 and associated parts. The clutch member 23 shown in Figure 3 is provided with an angular lug 30 adapted to fit into a corresponding depression or socket 31 in the companion clutch member 24. The clutch member 23 is also provided with a pin 32 adapted to fit into a hole 33 in the clutch member 24. The pin 32 is diametrically opposed to the lug 30 and it will be understood that the lug and pin when engaging the socket 31 and the hole 33 serve to transmit power from the clutch member 24 to the shaft 22.

Whenever the contacts of the distributor 3 or of the contact breaker 5 get out of order, or any other part of the ignition apparatus, above described, becomes disarranged so that the ignition system fails to supply current to the spark plugs, it would ordinarily be necessary to repair the system at once before the engine could be made to operate in a satisfactory manner. My invention makes it unnecessary to repair the ignition apparatus which has become disarranged or out of order because additional ignition apparatus is provided and arranged

in such a manner that it can be connected up with the spark plugs and the crank shaft by merely operating the control rod 19.

When the control rod 19 is moved in the direction opposite to that indicated by the arrow in Figure 1, the switch 11 is moved into the position shown in this figure and the lever 19 is moved so as to disconnect the clutch members 23 and 24. This disconnects the distributor 3 and all parts associated therewith from the crank shaft, and disconnects the distributor 3 from the spark plugs *a*, *b*, *c* and *d*. This movement of the control rod 19 thus completely disconnects the ignition apparatus above described; and it serves to connect a second ignition apparatus into operative relation to the engine.

The second set of ignition apparatus may be substantially a duplicate of that above described and it is so shown in the accompanying drawings. A distributor 34 having a movable contact arm 18' is connected to contacts *g'*, *h'*, *i'*, and *j'* of switch 11 by means of leads 35, 36, 37 and 38. The contact *f'* of switch 11 is connected to a contact breaker 40 by means of a lead 39. The contact breaker 40 is, in turn, connected to the primary winding of a spark coil 41 by means of a lead 42. A magneto 43 driven by a shaft 44 is connected to the contact breaker 40 by means of a lead 45. The shaft 44 is driven by the crank shaft 2 through clutch members 46 and 47 and driving chains 48 and 28.

If, for any reason, the distributor 3 should get out of order or in fact any of the parts associated with this distributor, then by simply moving the rod 19 in the direction opposite that indicated by the arrow, the distributor 3 and the generator 20 associated therewith can be disconnected from the spark plugs and the distributor 34 and the generator 43 connected to the spark plugs in their place.

The movement of the rod 19 serves to disconnect the clutch members 23 and 24 and connect the clutch members 46 and 47. This movement of the rod also serves to move the switch 11 so as to connect the distributor 34 to the spark plugs and to connect the battery 6 to the contact breaker 40 and the generator 43.

The magnetos 20 and 43 shown in Figure 1 of the accompanying drawings are illustrated as being of the type having a field winding supplied with excitation current from the battery 6. It will be understood, of course, that magnetos of the common type having a field structure consisting of merely a permanent magnet may be employed. The battery 6 may be connected to the spark coils 4 and 41 through the contact breakers 5 and 40 respectively. When this is done, energy is supplied to the set of spark plugs by the battery and it will be

understood that this connection is employed only in case both magnetos are out of order. The generators 20 and 43 shown in Figure 1 may be of the direct current type or of the 5 alternating current type.

The embodiment of my invention illustrated in the accompanying drawings thus includes means for connecting either of two distributors to a set of spark plugs, at least 10 one source of electrical energy, and manually operable means for selectively connecting the distributors so as to receive electrical energy. In this way, the proper operation of the engine is assured at all times because 15 if the distributor or magneto supplying the electrical energy to the engine should get out of order, the second set of ignition apparatus can be immediately brought into play.

It is to be understood that my invention 20 is not limited to the particular embodiment illustrated and described but includes such modifications thereof as fall within the scope of the appended claims.

I claim:

25 1. An ignition system comprising the combination with a set of spark plugs, of two distributors, means for separately connecting each distributor to the set of spark plugs, at least one source of electrical energy, 30 and manually operable means for selectively connecting the distributors so as to receive electrical energy.

2. An ignition system comprising the combination with a set of spark plugs, of two 35 distributors each having a movable contact arm, separate means for driving each of said contact arms, a source of power for said driving means, means for separately connecting each distributor to the set of spark plugs, at least one source of electrical 40 energy, and manually operable means for simultaneously connecting one distributor so as to receive electrical energy and connecting the driving means for this distributor to the source of power.

45 3. An ignition system comprising the combination with a set of spark plugs, of a distributor having a movable contact arm, means for driving the contact arm of said 50 distributor, a source of power for said driving means, means for connecting the distributor to each of the spark plugs, a source of electrical energy, and manually operable means for simultaneously connecting the 55 distributor so as to receive electrical energy from said source and connecting the driving means for this distributor to the source of power.

60 4. An ignition system comprising the combination with a set of spark plugs, of two distributors each having a movable contact arm, separate means for driving each of said

contact arms, a source of power for said driving means, means for separately connecting each distributor to the set of spark 65 plugs, at least one source of electrical energy, and manually operable means for simultaneously disconnecting one distributor from a source of electrical energy and connecting the other distributor so as to receive 70 electrical energy, and connecting the driving means for this last mentioned distributor to the source of power.

5. An ignition system comprising the combination with a set of spark plugs, of two 75 distributors each having a movable contact arm, a generator associated with each distributor, separate means for driving the contact arms of said distributors and the generators associated therewith, a source of power for said driving means, means for separately connecting each distributor to the set of spark plugs, and manually operable means for simultaneously connecting either 80 of said driving means to said source of power.

6. An ignition system comprising the combination with a set of spark plugs, of two 85 distributors each having a movable contact arm, a battery, a generator associated with each distributor, separate means for driving the contact arms of each of said distributors and the generators associated therewith, a source of power for said driving means, means for separately connecting each distributor to the set of spark plugs, and manually operable means for simultaneously connecting said battery to one of said distributors and connecting the driving means 90 for the generator associated with this distributor to the said source of power.

7. An ignition system comprising the combination with a set of spark plugs, of a double throw switch, having movable and stationary contacts, means for connecting movable contacts of said switch to the spark plugs, two distributors each having a movable contact arm, means for connecting each distributor to stationary contacts of said 105 switch, a battery connected to a movable contact of said switch, a generator for each of said distributors, separate means for driving each of said generators and the movable arms of the distributors associated therewith, a source of power, a clutch interposed between said source of power and each means for driving said generators, and manually operable means for simultaneously operating said switch and said clutches whereby either distributor and its associated generator 110 can be connected to the spark plugs to supply energy thereto.

In testimony whereof I affix my signature.
FRANK GUELCHER.
